(57) **CLAIM**

The ornamental design for a data transmission device for use in combat harness as shown and described.

DESCRIPTION

1. Data transmission device for use in combat harness
 FIG. 1.1: back view; FIG. 1.2: front view; FIG. 1.3: right view; FIG. 1.4: left view; FIG. 1.5: top view; FIG. 1.6: bottom view.

The broken lines form no part of the claimed design.

1 Claim, 5 Drawing Sheets

FIG. 1.1

FIG. 1.2

FIG. 1.3

FIG. 1.4

FIG. 1.5

FIG. 1.6
